DESIGN FOR A NECKLACE

Maximilian C. Meyer, Brooklyn, N. Y.

Application June 20, 1940, Serial No. 93,150

Term of patent 3½ years

To all whom it may concern:

Be it known that I, Maximilian C. Meyer, a citizen of the United States, residing at Brooklyn, in the county of Kings and State of New York, have invented a new, original, and ornamental Design for Necklace, of which the following is a specification, reference being had to the accompanying drawing, forming a part thereof.

The figure is a perspective view of a necklace showing my new design.

The essential feature of my design resides in a necklace comprising a multiplicity of graduated spherical plastic pendants arranged on the chain as shown, said pendants being characterized by a light reflecting band area about the peripheries thereof.

I claim:

The ornamental design for a necklace, as shown and described.

MAXIMILIAN C. MEYER.
